AUTOMATIC COMPENSATING CENTRIFUGAL GOVERNOR

Walter E. Benjamin, Anderson, Ind., assignor to
Pierce Governor Company, Anderson, Ind.

Application January 30, 1943, Serial No. 474,095

14 Claims. (Cl. 123—108)

This invention relates to centrifugal governing of engines utilizing a combustible mixture such as a gas or gasoline engine.

In an engine of this character the governing element is usually a butterfly valve and since the governing force is externally applied to the governing valve and by a centrifugal device responsive member this valve usually is of balanced butterfly type and is mounted in a throttle body inserted between the carburetor and intake manifold. The balanced valve eliminates to a great extent the velocity effect of the fuel supply thereon over the unbalanced valve, hence is preferred.

In governing of the aforesaid character the control structure is directly responsive to engine speed, and in the type illustrated, static and velocity pressures on governing valves vary, so that the torque exerted thereon by fuel mixture flow through the engine intake varies for different speeds and loads, etc.

The chief object of this invention is to offset this uneven torque pressure on the governing throttle valve, so that the latter is truly directly and proportionally responsive to the centrifugal control imposed on said valve.

The result is that extremely close governor regulation between no load and full load is possible, because the torque reactions on said valve between these loads is properly compensated for.

The chief feature of this invention resides on the inclusion of governor valve torque pressure compensator in the form of a cam and follower structure that is arranged to impose a force on said valve at any position thereof substantially equal and opposite to the fuel mixture flow torque imposed thereon, with the result that there is in effect a negligible pressure result, or a pressure that is substantially constant for the full range of throttle valve travel.

The present invention is, as evidenced by the charts, a substantially perfect exemplification of the basic invention disclosed in the copending application Serial No. 452,883 filed July 30th, 1942 although same is confined to a velocity governor only and incorporates therein a compensating factor.

The present invention in like manner produces results that are phenomenal in that almost vertical line effect results at any governed speed for all loads. No governing structure known to date is comparable thereto. Applied to military equipment, as it now is, this invention holds the engine to the governed speed, so that approximately 25 B. H. P. additional is now available

for hill climbing purposes and about four miles per hour more speed is available over the entire range of from no load to full load, for governed speed at full load.

Other objects and features of the invention will be set forth more fully hereinafter.

The full nature of the invention will be understood from the accompanying drawings and the following specifications and claims:

10 In the drawings Fig. 1 is a diagrammatic central sectional view of a conventional centrifugally operable device, a side elevation of a governor throttle body, the power connection therebetween and a side elevation of the valve torque compensating structure, parts being shown in the wide open throttle position, dotted lines indicating the governor valve closed throttle position.

Fig. 2 is an end elevational view of the throttle body with governor connection and compensating structure attached.

Fig. 3 is a diagram of two curves from wide open throttle to closed throttle over a full range of 60° and in. pounds of valve torque at that position, the full line being taken from a Wright 25 R975 motor and the dotted line being taken from the compensating device therefor, as correlated thereto, showing substantially exact conformance in curve shape as well as values for the same degrees of throttle valve opening.

30 Fig. 4 is a diagram of the curves for the invention applied to R-975-C1 Continental Motor Serial No. 130,078 with spring set for 3½ in. pounds at 30°, the first curve showing manifold pressure against speed, the second showing brake 35 horsepower load against speed, and the third showing beam load of the brake against speed, the former all being the variable and the latter being substantially 2400 R. P. M. These curves are substantially constant vertical lines indicating 40 constant regulation at any load and for different manifold pressure evidencing substantially exact and complete compensation from no load to full load at a given speed.

Fig. 5 is a diagrammatic side elevation of an 45 engine including air cleaner, carburetor, manual throttle, manifolds, throttle body, governor (engine driven) and connection therefrom to throttle valve shaft in the throttle body X indicating the valve and Y the manual control.

50 The corresponding curves for the device set forth in the copending application show a slight inclination crossing the selected speed near the higher vacuums or positive pressures and high load markedly broke to the left in this range. 55 Valve torque compensation being substantially

perfect in the present invention, there is none to transmit to the governor, so that surging back and forth to correct over a limited range (hunting) substantially is eliminated to a degree heretofore unknown in a centrifugal governor mechanically connected to a throttle valve.

In Fig. 1 of the drawings, 10 indicates a housing of a centrifugally operable structure secured to a portion of the engine by bolts 11 and having a lateral opening by which a gear 12, keyed at 13 to the centrifugal shaft 14, can engage and mesh with an engine, or engine driven gear, so that shaft 14 is rotatable at, or proportional to engine speed.

Shaft 14 is rotatably supported in anti-friction bearings 15 and 16, the latter being mounted in the housing extension 10a. Longitudinally slideable on, but rotatable with shaft 14, is sleeve 17. Rigid with shaft 14 is base 18, to which is pivoted at 9 the centrifugal force responsive weights 20, having tail or finger portions 21 positioned adjacent one end of sleeve 17.

At a predetermined engine speed, determinable by the load spring adjustment and spring selected, these weights, due to centrifugal force, tend to move outwardly and upon doing so, their tail portions slide sleeve 17 upon shaft 14. Herein in sleeve 17 is illustrated as mounting an anti-friction bearing member 22 at the end opposite the tail engageable portion.

A yoke lever pivoted at 23 has spaced portions 24 engageable by bearing 22. Thus the lever 25 is tiltable by weight movement responsive to centrifugal force. A load spring 26 bears at 27 upon lever 25, being retained thereon by stem guide 28. Housing 10 is threadedly apertured at 29 and an externally threaded socket type cap, having socket 30 and knurled head 32, seats the other end of said spring, and may be manually rotated, respectively, for adjusting the initial force of such load spring. Lock nut 31 holds the adjustment.

This spring normally opposes centrifugal movement of the weights at all times. When the centrifugal force is sufficiently great, the weights move, as described, and hence tilt lever 25. This is the control lever and is usually connected to the governing member, such as a butterfly valve in a passage through a throttle body in the engine intake system.

All of the aforesaid describes a conventional centrifugal governor, and in the present invention the same is not disturbed, but the effect of other forces, as initially described herein, are of such character that this theoretical operation is modified to that extent. The present invention automatically compensates for such forces, so that the actual governing operation is substantially the theoretical operation.

Herein, see Fig. 1, lever 125 outside of the governor housing and rigid with shaft 23, supports a pin type end 33 of a rod 34, which may be of adjustable length type. At its opposite end, this rod is pivotally connected at 35 to a lever arm 36, rigid with an exposed end of throttle shaft 37, pivoted in throttle body 38 interposed in the engine intake system downstream of the carburetor and usually between the carburetor and engine manifold connecting flanges, see Fig. 1.

Herein shaft 37 projects through the body and on its other exposed end mounts another arm 41 pinned thereto as at 42. This shaft may be mounted in anti-friction bearings (not shown). The free end of arm 41 mounts on pivot 44, the

roller or follower 45. An anti-friction race 43 may be interposed between pivot 44 and roller 45 wherever desired or required.

The aforesaid several anti-friction bearings 5 broadly are conventional to standard governor practice, wherefor same are not illustrated in detail.

Pivotedly supported at 46 on the throttle body, and adjacent arm 41, is member 47. The roller 10 and member 47 lie in a common plane. Member 47 is of bell crank type with arm 48 having flat face 49 perpendicular to line A-B and lying in the plane including the axis of shaft or pivot 46. Roller 45 contacts face 49 at all times. The other arm 50 of bell crank 47 has eye 52 in its outer end and the center thereof lies in plane A-B. Accordingly, plane of face 49 is at right angles to center of the eye 52.

A light spring 51 has one end secured to eye 52 and its opposite end is secured to eye 53 in the anchor member 54 threaded into boss 55 on plate 56 rigid with the throttle body. The spring ends are aligned at wide open throttle, for the longitudinal axis of anchor member 54 lies in plane A-B. The tension of this spring, which is light, but sufficient for compensating purposes, can be adjusted by moving member 54 toward and away from the axis of pivot 46.

Obviously the spring 51 always constrains the face 49 into roller contact, so that the force of this spring tends to hold the valve open and in an amount equal to the torque on the valve imposed by fuel flow in the intake when the governor valve is moved toward closed position. This torque is in the valve closing direction. The spring force is opposed thereto.

Now, as the valve is governor closed the arm 48 must move clockwise. In so doing arm 50 moves therewith. Now, since spring 51 is under initial tension, it, when the arm is so moved elongates or stretches, hence its force increases as the arm is moved.

Here follows the gist of this invention and the key to its success. Observe, see Fig. 1, that at open valve position the arm 41 lies parallel to arm 48. When spring 51 is adjusted, this is the idle or non-governing position. With a balanced valve the fuel flow torque thereon is zero, see curve Fig. 3.

Now, with a 60° throttle valve movement to closed throttle, the arm 41 is then transverse to arm 48. Also, the torque curve again is zero, because now no fuel flows in the intake. However, at this position spring 51 is more elongated than ever.

With the valve half open, the torque is greatest. In this position arms 41 and 48 are midway between the aforesaid limiting positions and spring 51 is elongated, but partially from idle zero position to its finally extended position.

The actual effective spring balancing force, accordingly, from 30° to 60° of throttle valve is proportionately decreased despite its (the spring) extension or increase. This is because so far as arm 41 is concerned, the pressure of arm 48 thereon, effective to throw the valve open, if the governor force be removed, (or "flip open") is only the decreasing regular function thereof, from 30° to 60°, respectively.

This explains why there is not an absolutely vertical line in Fig. 4, and this angular function cancellation is exactly equal in amount at all valve positions to produce an actual sine curve balancing force, compare the two curves in Fig. 3.

However, the curves are so close as to be substantially identical with the results described.

The mechanical advantages of the present invention over that disclosed in the pending application are that first in common therewith a longitudinally extensible spring is utilized, but herein the adjustment possible can be of micrometer variation, which is impossible in the assemblage of said application. This means that the slight variations which always are present in a lot of commercial springs of a specified diameter, length and force, can be readily adjusted for, in effect eliminated, so that accurate spring selection is not required. A more important advantage, however, exists in that a flat face is always a flat face and, hence, no variation occurs in manufacture. Such is not the case with the sinusoidal face of the application cam. The least variation in the face at any point will introduce an error in the correction desired. Also, there is a mechanical function error inherently present in said pending application structure for which no compensating internal correction is provided and this accounts for the departure of its curves from the curves herein, as previously mentioned.

All the aforesaid, however, is solely intended to show that present invention is substantially perfect, whereas the invention disclosed in the pending application, while phenomenally better than any heretofore known, actually did not reach perfection, although it was very close thereto.

While the invention has been illustrated and described in great detail in the drawings and foregoing description, the same is to be considered as illustrative and not restrictive in character.

The modification described herein, as well as others which will readily suggest themselves to persons skilled in this art, all are considered to be within the broad scope of the invention, reference being had to the appended claims.

The invention claimed is:

1. In an engine governing mechanism including a substantially balanced butterfly valve for engine intake throttle control and a centrifugally operable structure responsive to engine speed and directly connected to said valve for operation thereof, the combination of an arm rigid with said valve, a bell crank lever adjacent thereto, having an arm with an elongated flat face for operatively engaging the end of the valve, at wide open throttle position the longitudinal axis of the valve arm lying parallel to the plane of the face and at closed throttle being substantially transverse thereto, said bell crank having another arm, the free end thereof forming a spring anchorage, the longitudinal line including such anchorage and the lever pivot axis being substantially perpendicular to the plane of the face, another spring anchorage in alignment with the longitudinal line only when the aforesaid parallelism exists, and a coiled light tension spring secured at opposite ends to said anchorages for substantially perfect compensation for the intake fuel flow torque on said valve for substantially all governed positions of said valve and constraining the bell crank to valve arm contact.

2. A governing mechanism as defined by claim 1 wherein the plane of the flat face passes through the pivot axis of the bell crank lever.

3. A governing mechanism as defined by claim 1 wherein the spring ends are of loop character

and lie in a common plane common to the longitudinal line and substantially transverse to the face plane.

4. A governing mechanism as defined by claim 1 wherein the spring ends are of loop character and lie in a plane common to the longitudinal line and substantially transverse to the face plane, the latter plane passing through the pivot axis of the bell crank lever.
5. A governing mechanism as defined by claim 1 wherein the second mentioned spring anchorage is an eyeleted elongated threaded member for wide open throttle initial spring force adjustment and commercial spring variation compensation.
6. A governing mechanism as defined by claim 1 wherein the valve arm terminates in a flat face roller follower, the axis of which roller lies perpendicular to and intersects the longitudinal axis of said valve arm.
7. A governing mechanism as defined by claim 1 wherein the valve arm terminates in a flat face roller follower, the axis of which roller lies perpendicular to and intersects the longitudinal axis of said arm, and there is included an anti-friction support between the roller follower and the valve arm.
8. A governing mechanism as defined by claim 1 wherein the valve arm terminates in a flat face roller follower, the axis of which roller lies perpendicular to and intersects the longitudinal axis of said valve arm, and the second mentioned spring anchorage is an eyeleted elongated threaded member for wide open throttle initial spring force adjustment and commercial spring variation compensation.
9. A governing mechanism as defined by claim 1 wherein the valve arm terminates in a flat face roller follower, the axis of which roller lies perpendicular to and intersects the longitudinal axis of said valve arm, and there is included an anti-friction support between the roller follower and said valve arm, and the second mentioned spring anchorage is an eyeleted elongated threaded member for wide open throttle initial spring force adjustment and commercial spring variation compensation.
10. A governing mechanism as defined by claim 1 wherein the valve arm terminates in a flat face roller follower, the axis of which roller lies perpendicular to and intersects the longitudinal axis of said valve arm, and there is included an anti-friction support between the roller follower and said valve arm, and the plane of the flat face passes through the pivot axis of the bell crank lever.
11. A governing mechanism as defined by claim 1 wherein the valve arm terminates in a flat face roller follower, the axis of which roller lies perpendicular to and intersects the longitudinal axis of said valve arm, and there is included an anti-friction support between the roller follower and the valve arm, and the plane of the flat face passes through the pivot axis of the bell crank lever.
12. A governing mechanism as defined by claim 1 wherein the spring ends are of loop character and lie in a common plane and common to the longitudinal line and substantially transverse to the face plane, the second mentioned spring anchorage is an eyeleted elongated threaded member for wide open throttle initial spring force adjustment and commercial spring variation compensation.
13. A governing mechanism as defined by claim 1 wherein the spring ends are of loop character and lie in a common plane and common to the

longitudinal line and substantially transverse to the face plane, the latter passing through the pivot axis of the bell crank lever, the second mentioned spring anchorage is an eyeletted elongated threaded member for wide open throttle initial spring force adjustment and commercial spring variation compensation.

14. In an engine governing mechanism including a substantially balanced butterfly valve for engine intake throttle control and a centrifugally operable structure responsive to engine speed and directly connected to said valve for operation thereof, the combination of an arm rigid with said valve and a single elongated tension spring anchored at one end and operatively connected at its other end to said arm remote from the

valve axis thereof, said arm at open valve position having a general direction angular to the plane of the valve, the general direction of the spring at open valve position being angular to said arm and the plane of the valve, the spring-arm relationship at open valve position being such that substantially no spring force is effective upon the valve, and at closed valve position substantially no spring force is effective upon the valve, the force, direction and effect of said spring varying therebetween for loading the valve to compensate for velocity effect thereon between said extreme positions thereof, the spring in intermediate valve positions, pulling towards open valve position.

15
